UNITED STATES PATENT OFFICE.

CALVIN L. VAN NORSDALL, OF ARMA, KANSAS, ASSIGNOR OF ONE-FOURTH TO
WILLIAM L. WEIR, OF WEIR, KANSAS.

AUTOMATIC LUBRICATING DEVICE.

1,168,129.

Specification of Letters Patent. Patented Jan. 11, 1916.

Application filed October 19, 1914. Serial No. 867,446.

To all whom it may concern:

Be it known that I, CALVIN L. VAN NORSDALL, a citizen of the United States, residing at Arma, in the county of Crawford, State 5 of Kansas, have invented certain new and useful Improvements in Automatic Lubr- 60 icating Devices; and I do hereby declare the following to be a full, clear, and exact de- 65 scription of the invention, such as will en- 70 able others skilled in the art to which it ap- 75 pertains to make and use the same.

This invention relates to certain novel and useful improvements in an automatic lubri- 15 cating device, adapted especially for lubri- 20 cating the journal bearings of mine car wheels.

In carrying out my invention it is my pur- 25 pose to provide a lubricating device which is adapted to be operated by the wheel of 30 the car to permit the lubricant to be sup- 35 plied to the journal bearing of such wheel, the parts being automatically returned to 40 their normally inoperative position after the 45 wheel has been lubricated so that the device 50 is ready for the lubrication of the next 55 wheel.

Still a further object of my invention is 60 the provision of lubricating apparatus of 65 this character which is adapted to be located 70 alongside the trackway so that the car 75 wheels may be quickly, thoroughly and suc- 80 cessively lubricated.

With the above recited objects and others 85 of a similar nature in view, my invention 90 consists in the construction, combination and 95 arrangement of parts set forth in and fall- 100 ing within the scope of the appended claims.

In the accompanying drawings: Figure 1 105 is a view partly in side elevation and partly 110 in section of a device embodying my in- 115 vention, and showing a car wheel in the act of 120 being oiled. Fig. 2 is a top plan view. Fig. 125 3 is an end view. Fig. 4 is a cross sectional 130 view taken on the line 4-4 of Fig. 1. Fig. 135 5 is a similar view taken on the line 5-5 140 of Fig. 1. Fig. 6 is a cross sectional view 145 taken on the line 6-6 of Fig. 1.

Referring now to the accompanying draw- 150 ings in detail, the letter A designates a base 155 having mounted to slide thereon a table 1 160 which is provided with an extension or 165 flange 2 depending from the bottom thereof 170 and extending through a slot 3 in the base A. 175

Carried by this table is a post 4 having piv- 180 55 otted thereto as at 5, a rod 6 having a break 185 pivot 6' and a spring 6'' normally holding 190

the two parts of the rod in alinement. The 195 forward end of the rod is provided with a 200 roller 7 adapted to be contacted with by the 205 wheel W which is to be oiled. The axle box- 210 ing of the wheel is shown at W and is pro- 215 vided with the usual oil port. The rear end 220 of the pivoted rod 6 is pivotally connected 225 as at 8 to the link 9, said link being pivoted 230 adjacent its opposite end as at 10 to the ver- 235 tical link 11, this latter link being pivoted 240 as at 12 to the table. The cross link 14 is 245 connected by the pivot 10 to the links 9 and 250 11, and is further pivoted at its forward end 255 as at 15 to the trip bar 16, the latter being 260 pivoted as at 17 to the post 4, the lower end 265 of said trip bar being adapted to contact 270 with the stop 18 located below the base A for 275 the purpose hereinafter described.

Carried by the sliding table 1 is a pipe 19, 280 the horizontal section 20 of which is pro- 285 vided with a bored piston head 21 sliding in 290 the oil cylinder 22, this cylinder being sup- 295 plied with oil through a supply pipe 23 300 leading to a suitable point of supply, such 305 as a tank or the like. The vertical section 310 24 of the pipe 19 extends above the table 315 and is of sufficient height to align with the 320 port in the axle boxing w of the car wheel 325 when the latter is moved into position to be 330 oiled. As will be seen by reference to Fig. 335 4, the upper end of this pipe section 24 is 340 formed with a reduced outlet 25, and on the 345 end of the pipe is applied a spring nozzle N, 350 comprising a casing 26, through an opening 355 27 in the forward end of which slides a tubu- 360 lar stem 28 having its inner end provided 365 with an imperforate convex head 29, while 370 its outer end is provided with a convex head 375 30 having an outlet opening or port 31 380 therein. The stem is further provided with 385 longitudinal slots 32 extending from points 390 adjacent the head 29 to approximately the 395 center of the stem. An expansion spring 33, 400 bearing at one end against the head 29 and 405 at its opposite end against the outer end 410 wall of the casing 26 normally acts to hold 415 the head 29 seated or closed against the out- 420 let end 25 of the pipe 24. When, however, 425 there is sufficient pressure of oil in the pipe 430 24, as when a car wheel W moves into posi- 435 tion to bring the axle boxing against the 440 head 31 of the nozzle, the pressure of oil 445 will force the stem 28 outward against the 450 tension of the spring 33, moving the head 455 29 away from the end 25 of the pipe 24 and 460 the oil will flow into the casing 26, through 465

the slots 32 into the tubular stem and through the port or opening 31 in the head 30 to the axle boxing.

In the operation of the device it is to be understood that as the car travels along the trackway T, the wheel to be oiled will contact with the roller 7, thus pulling downward upon the bar 6, and as this bar is connected with the post 4 of the table 1 by means of the pivot 5, this table is pulled forward, and as the oil pipe 19 is carried by the table the piston head 21 will be moved forward in the oil cylinder 22 and the oil will be forced through the horizontal pipe section 20, up the vertical pipe section 24 and injected through the spring nozzle N in the axle bearing. When the piston has thus been pushed forward to substantially the limit of its movement toward the forward end of the cylinder 22, the lower end of the trip bar 16 will strike against the stop 18, thus bringing the lower end or contacting end of the trip bar rearward and throwing the upper end thereof forward. This causes a forward pull upon the link 14 and pulls forward upon the toggle link formed of the link members 9 and 11, and when this toggle link moves to the left or opposite to the position shown in Fig. 1, the rod 6 carrying the roller 7 will be pulled upon its pivot 5 so that the roller may be moved upward to permit the car wheel to pass. At the same time the table is returned to its normally inoperative position by means of a relatively powerful spring connected as at 35 to the flange 2 of the table 1. When the table has thus been returned to its normal position after the oiling of the wheel has taken place, the piston head 21 is of course, drawn back with the pipe 19 and the oil is permitted to flow into the oil cylinder 22 refilling the latter ready for the next car. It will, of course, be understood that the amount of oil used may be determined and gaged by the stop 18 so that when the trip bar has moved up a short distance to strike the stop 18, but a small amount of oil will be supplied, while the greater the distance the trip bar has to move to strike the stop 18, the greater will be the amount of oil supplied.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is:

1. The combination with a sliding sup-

port, of a member carried thereby and adapted to be contacted with by a wheel to be oiled to move the support, of an oil pipe 65 carried by the sliding support, and having a nozzle adapted to discharge the oil into the wheel bearing, an oil cylinder located adjacent the sliding support, and a piston carried by the oil pipe and working in said cylinder, and means for returning the sliding support to its normally inoperative position.

2. The combination with a movable support, of an oil cylinder located adjacent thereto, a piston working in said cylinder, an oil pipe connected with the piston and carried by the movable support, said pipe terminating at its upper end in a discharge opening through which the oil is discharged 80 to the bearing of the wheel to be oiled, means carried by the movable support adapted to be contacted with by the car wheel to move the support and cause the oil to be discharged from the cylinder through the oil 85 pipe to the wheel, and means for returning the support to its normal position.

3. The combination with a movable support, of an oil pipe carried thereby and having a discharge end through which the oil is adapted to flow to the bearing of a wheel to be oiled, means carried by the movable support adapted to be contacted with by the wheel to be oiled to move the support and cause the oil to be discharged 95 through the oil pipe, means for throwing said contact means out of contact with the wheel, and means for returning the movable support to its normal position.

4. The combination with a base, of a support sliding thereon, an oil pipe carried by the sliding support and terminating at one end in a piston and at its opposite end in a discharge nozzle adapted to discharge the oil to the bearing of the wheel to be lubricated, an oil cylinder arranged adjacent the base and within which the piston moves, a bar pivotally mounted on the support and terminating at one end in a contact member adapted to be struck by the car wheel to be 110 oiled and to move the sliding support forward on its base, to cause the movement of the piston in the cylinder and discharge the oil to the wheel, tripping means for moving said contact member out of contact with the wheel after the latter has been oiled, and means for returning the sliding support to its normal position.

In testimony whereof, I affix my signature, in the presence of two witnesses.

CALVIN L. VAN NORSDALL.

Witnesses:

W. A. DE LAPP,

FRED WRIGHT.
